No. 852,685.

PATENTED MAY 7, 1907.

R. G. SPEER.
CARBURETING APPARATUS.
APPLICATION FILED JUNE 15, 1906.

Attest:

M. H. Holmes.

Henry Moe,

Inventor!

Robert G. Speer,

by Robert Burns, Attorney.

UNITED STATES PATENT OFFICE.

ROBERT G. SPEER, OF ST. LOUIS, MISSOURI, ASSIGNOR, BY DIRECT AND MESNE ASSIGNMENTS, OF ONE-FOURTH TO J. J. HOLSCHER AND THREE-FOURTHS TO SARAH B. SPEER, BOTH OF ST. LOUIS, MISSOURI.

CARBURETING APPARATUS.

No. 852,685.

Specification of Letters Patent.

Patented May 7, 1907.

Application filed June 15, 1906. Serial No. 321,791.

To all whom it may concern:

Be it known that I, ROBERT G. SPEER, a citizen of the United States of America, and a resident of the city of St. Louis and State 5 of Missouri, have invented certain new and useful Improvements in Carbureting Apparatus, of which the following is a specification.

This invention relates to an apparatus for carbureting air for lighting and heating purposes, and has for its object to provide a simple and durable structural arrangement and combination of parts whereby an effective carbureting of the air is effected, and the 10 flow of air through the apparatus rendered constant with a consequent avoidance of the fluctuations in the flame of the burners where the combustion of the carbureted air takes place, all as will hereinafter more fully 15 appear.

The accompanying drawing is a central vertical section of an apparatus embodying the present invention.

Referring to the drawings, 1 represents the 20 carbureter of the present apparatus, consisting of a closed casing provided with an induction pipe 2 near its lower end, and a corresponding eduction pipe 3 at its upper end.

4 is a porous partition arranged near the 25 mid-height of the carbureter casing, to divide the same into a lower containing chamber for the supply of gasolene, and into an upper containing chamber for the carbureted air.

30 5 is a distributing tank arranged centrally in the upper end of the carbureter casing and provided with a contracted outlet orifice 5' at its lower end.

6 is a distributing trough arranged beneath the distributing tank and adapted to 35 receive the limited outflow from the same, and in turn discharge the gasolene down upon the porous partition 4 in the bottom of said tank.

45 7 is a pipe connecting the lower end of the distributing tank 5, with the lower part of the carbureter casing containing the supply of gasolene.

8 is a check valve arranged in the pipe 7 to 50 prevent a back flow of the gasolene from the distributing tank 5, aforesaid.

9 is a simple acting pump, arranged and

operated in the manner hereinafter described, and connected by pipe 10 with the top of the distributing tank 5; the arrangement is such 55 that with an active stroke of such pump the air will be exhausted from the upper end of the tank 5, and in consequence a fresh supply of gasolene will be drawn into said tank through the pipe 7 from the main supply in 60 the lower end of the carbureter casing.

11 and 12 are a pair of stationary pump cylinders, in the form of open top vessels the walls of which are formed double to provide annular water containing chambers or seals 65 13 and 14 for the movable pistons of the pumps or compressors.

15 and 16 are a pair of inverted bell pistons, having annular depending skirts which dip into the annular seals 13 and 14, as 70 shown.

With the described arrangement of pump cylinders and pistons, the usual closed central air compression chambers 18 and 17 are provided, and the capacities of which are alternately increased and diminished by the vertical reciprocation of the pistons with relation to the cylinders, to alternately draw in air from the outer atmosphere, and compress and force said air to other portions of the apparatus, as hereinafter more fully set forth. 75

19 is a crown plate closing the top of the inner vertical wall of the pump cylinder 11 to form a chamber 20 under constant and normal atmospheric pressure, and which to this 80 end is provided with an orifice 21 forming a constant communication with the outer air.

22 is a check valve controlling an inlet passage through said crown 19, and through which air is admitted to the compression 90 chamber 17 of the pump.

23 is an outlet pipe communicating with the compression chamber 17, and extending to the storage and pressure regulating tank hereinafter described; such pipe is provided with a branch portion 24, which connects with the compression chamber 18 of the other pump to act as an inlet-outlet pipe to said chamber in the normal operation of the chamber. 95

100 25 is a supplementary inlet passage to the compression chamber 18, and 26 is a check valve controlling said passage. The said passage and valve are supplementary to inlet-

outlet branch pipe 24, and in some cases may be omitted without affecting the normal operation of the apparatus.

27 is the storage and pressure regulating tank before referred to; and such tank comprises a stationary open top vessel formed with double walls to provide an annular water containing chamber or seal 28; and a vertically moving inverted bell piston 29, having an annular depending skirt which dips into the annular seal 28 aforesaid.

30, 31 and 32 are weights attached to the respective pistons 15, 16 and 29 to afford the requisite downward stress in attaining the desired compression of the air passing through the apparatus.

33 is a check valve at the eduction end of the pipe 23, before described, to prevent a reflux of the compressed air from the storage and pressure regulating chamber 27, aforesaid.

34 is a horizontal beam attached to the upper ends of the bell pistons 15 and 16 to form a common operating connection for the two pistons.

35 is a flexible connection attached centrally to the beam 34, and having in turn operative connection with a suitable automatic motor, so as to receive and impart simultaneous upward movements to the pistons aforesaid at proper intervals of time required in the operation of the apparatus. Such automatically operating motors are quite common in the present type of apparatus and does not constitute any part of the present invention.

36 is a vertical guide rod fixedly secured to

the center of the horizontal beam 34, aforesaid, and adapted to have sliding movement in a fixed tube 37 secured to a stationary part of the apparatus, and adapted to impose vertical movement on the bell pistons of the pumps.

38 is a vertical rod extending from one end of the beam 34, and connected to the piston of the single acting pump 9, before described, and adapted to impart movement to said piston in unison with the bell pistons of the air pumps aforesaid. As so connected the pump 9 will have a central arrangement in the compression chamber 18, as shown.

Having thus fully described my said invention, what I claim as new and desire to secure by Letters Patent, is:—

In a carbureting apparatus, the combination of a carbureter, a pair of tank and bell pumps, one of which is formed with an interior chamber open to atmospheric pressure, means for imparting simultaneous reciprocation to said pumps, a storage and pressure regulating tank arranged in said interior chamber, a simple acting pump arranged in the interior of the other tank and bell pump and adapted to circulate the fluid contents of the carbureter, and pipe connections between the tank and bell pumps and the storage tank and between the storage tank and the carbureter.

Signed at St. Louis Missouri, this 12th day of June 1906.

ROBERT G. SPEER.
